(57) **CLAIM**

I claim the ornamental design for a water disinfectant generator, as shown and described.

DESCRIPTION

FIG. 1 is a front plan view of a water disinfectant generator showing my new design.

FIG. 2 is a right side elevational view thereof; the left side elevational view is a mirror image of the right side elevational view.

FIG. 3 is a top plan view thereof.

FIG. 4 is a bottom plan view thereof.

FIG. 5 is a perspective view thereof.

FIG. 6 is a perspective view thereof; and,

FIG. 7 is a back plan view thereof.

1 Claim, 4 Drawing Sheets(56)
